Primary Examiner — T Chase Nelson*Assistant Examiner* — Kelly L Gross(74) *Attorney, Agent, or Firm* — Muncy, Geissler, Olds & Lowe, P.C.(57) **CLAIM**

The ornamental design for a shaft attachable medical instrument, as shown and described.

DESCRIPTION

FIG. 1 is a front perspective view of a shaft attachable medical instrument according to the present invention.

FIG. 2 is a front view of the shaft attachable medical instrument of FIG. 1.

FIG. 3 is a rear view of the shaft attachable medical instrument of FIG. 1.

FIG. 4 is a left side view of the shaft attachable medical instrument of FIG. 1.

FIG. 5 is a right side view of the shaft attachable medical instrument of FIG. 1.

FIG. 6 is a top view of the shaft attachable medical instrument of FIG. 1; and,

FIG. 7 is a bottom view of the shaft attachable medical instrument of FIG. 1.
